(57) **CLAIM**

The ornamental design for an electric outlet, as shown and described.

DESCRIPTION

FIG. 1 is a perspective view of a first embodiment of an electric outlet, in accordance with my new design;

FIG. 2 is a front view of the electric outlet depicted in FIG. 1;

FIG. 3 is a perspective view of the electric outlet depicted in FIG. 1;

FIG. 4 is a front side view of the electric outlet depicted in FIG. 1;

FIG. 5 is a left view of the electric outlet depicted in FIG. 1;

FIG. 6 is a right view of the electric outlet depicted in FIG. 1;

FIG. 7 is a top view of the electric outlet depicted in FIG. 1;

FIG. 8 is a bottom view of the electric outlet depicted in FIG. 1; and

FIG. 9 is a back view of the electric outlet depicted in FIG. 1.

FIG. 10 is a perspective view of a second embodiment of an electric outlet, in accordance with my new design;

FIG. 11 is a front view of the electric outlet depicted in FIG. 10;

FIG. 12 is a perspective view of the electric outlet depicted in FIG. 10;

FIG. 13 is a front side view of the electric outlet depicted in FIG. 10;

FIG. 14 is a left view of the electric outlet depicted in FIG. 10;

FIG. 15 is a right view of the electric outlet depicted in FIG. 10;

FIG. 16 is a top view of the electric outlet depicted in FIG. 10;

FIG. 17 is a bottom view of the electric outlet depicted in FIG. 10; and,

FIG. 18 is a back view of the electric outlet depicted in FIG. 10.

In the drawings, the broken lines are for the purpose of illustrating portions of the electric outlet that forms no part of the claimed design.

1 Claim, 18 Drawing Sheets

Related U.S. Application Data

having an international filing date of Jun. 17, 2020,
now Pat. No. Des. 957,348.
